ATTORNEY

UNITED STATES PATENT OFFICE.

WILLIAM F. LITTLE, OF NEPPERHAN HEIGHTS, NEW YORK.

REFLECTOR FOR AUTOMOBILE HEADLAMPS.

1,427,216.

Specification of Letters Patent. Patented Aug. 29, 1922.

Application filed February 26, 1922. Serial No. 539,171.

To all whom it may concern:

Be it known that I, WILLIAM F. LITTLE, a citizen of the United States, residing at Nepperhan Heights, county of Westchester, State of New York (post-office address 75 Grand View Avenue, Nepperhan Heights, New York), have invented certain new and useful Improvements in Reflectors for Automobile Headlamps, of which the following is a full, clear, and exact specification.

In application for Letters Patent of the United States, filed February 26, 1921, Serial No. 447,980, Pat. 1,415,373 May 9, 1922, I describe certain new and useful improvements in automobile head lamps in which the light was distributed by a combination of paraboloidal and hyperboloidal reflectors so as to secure a concentrated light beam along the axis of the lamp, and oblique beams or bands of general illumination merging with the central beam and extending downwards and outwards therefrom for the purpose of illuminating the sides of the road; and in said application I point out the practical value of such light distribution especially for securing absence of glare in the eyes of an approaching driver, and the effectiveness of illumination both as to the center as well as the sides of the road.

My present invention relates to improvements by which I am able to secure a light distribution having the same advantages, and in which the reflectors used are hyperboloidal only. It is in fact possible to secure any desired type of beam from an automobile head lamp reflector, by the use of hyperbolic sections of properly proportioned axes. To secure the most concentrated beam the hyperbolic sections should have a transverse axis very much greater than the conjugate axis. To secure any degree of spread, axes should be selected accordingly and the values substituted in the equation of the hyperbola. Thus a reflector may be constructed of hyperboloidal sections alone which will project any desired combination of concentrated and spread beams as would be reflected from parabolic and hyperbolic sections as described in my said application. The hyperbolic sections may have either coincident axes or convergent or divergent axes, in order to overlap or separate the beams from each section, to build up the desired beam cross-section.

I will now describe my invention as ap-

plied to the formation of a beam having a central portion of high candle-power with two arms or bands extending to the right and left, the axes of the latter inclining downward and outward at angles of 25 to 30 degrees to the horizontal, and the arms or bands being graduated in candle-power from a high value in the center to a lower value at the extremities, reference being had to the accompanying drawing forming a part of this specification and in which:

Fig. 1 is a plan view of my improved reflector composed of six hyperboloidal sections;

Fig. 2, a vertical section thereof; and

Fig. 3, a diagram illustrating the beam reflected from the sections as the same would appear on a vertical screen.

In the above views, corresponding parts are represented by the same characters.

The reflector comprises sections 1, 2, 3, 4, 5, and 6, all of said sections being hyperboloidal. The relative areas of the sections may be varied somewhat, but as a convenient proportioning I make the section 1 to encompass an arc of 60°, the section 2 to encompass an arc of 70°, the sections 3 and 4 each encompassing an arc of 55°, and the sections 5 and 6 each encompassing an arc of 60°. The section 1 at the top of the reflector, has, as an illustration of a proper design, a focal length of one and one-quarter (1½) inches, with a transverse axis very long as compared with the conjugate axis. Such a section will project a highly concentrated beam A, as shown in Fig. 3.

The section 2 at the bottom of the reflector, may have a focal length of one and one-quarter (1½) inches, with a somewhat shorter transverse axis, thus projecting a beam B of somewhat wider spread, as shown in Fig. 3, and somewhat overlapping the beam A. The two sections 3 and 4, adjacent the section 2, have the same conjugate axes, and shorter transverse axes, the same focal length (one and one-quarter inches), and coincident axes. These two sections project two elliptical-shaped beams C and D, having portions which, as shown in Fig. 3, over-lap each other and also overlapping the central concentrated beam or at least a portion thereof. The transverse axes are inclined to the horizontal 27½° to the right and left. By thus properly proportioning the axes of these sections 3 and 4, I produce ellipses of illumina-

tion extending outwardly and downwardly six feet at a distance of one hundred feet from the reflector.

The remaining sections 5 and 6 are disposed on either side of the section 1, and with the latter comprise the upper half of the reflector. By these sections 5 and 6, I project ellipses E and F overlapping each other at a portion of their area as well as overlapping the ellipses C and D, and a portion of the central beam as shown in Fig. 3. These ellipses E and F have a transverse axis about fifteen feet long at a distance of one hundred feet from the reflector. In order that the ellipses may be projected downwardly and outwardly from the center of the concentrated portion of the beam, the axes of the sections 5 and 6 must intersect each other. The two planes in which these axes lie pass through the axes of the other hyperbolic sections and the two planes are inclined downward at an angle of 30° to the horizontal on the right and left. The axis of the two hyperbolic sections make an angle of 9° to the axes of the other hyperbolic sections.

The type of beam cross-section produced by this combination, as shown in Fig. 3, is therefore two small superimposed substantially circular patches of light A and B, projected from sections 1 and 2, two elliptical patches of light C and D, the transverse axes being approximately three times the conjugate axes and the transverse axes of these elliptical patches being disposed downward to the right and left at angles of 27½° to the horizontal; and the two elliptical patches of light E and F, with transverse axis approximately five times the conjugate axes and substantially similarly disposed.

Having now described my invention, what I claim and desire to secure by Letters Patent is as follows:

1. A reflector for automobile head lamps comprising hyperbolic sections, one of said sections projecting a central beam of high

candle-power, and two of said sections projecting oblique bands of light of less illumination, said bands overlapping each other, merging with a central beam and extending obliquely downward and outward to illuminate the sides of the road, substantially as set forth. 50

2. A reflector for automobile head lamps, comprising hyperbolic sections, two of said sections projecting superimposed beams of high candle-power, and two other sections projecting bands of reduced illumination, said bands overlapping the centrally superimposed beams and extending downward and outward to illuminate the sides of the road, substantially as set forth. 55

3. A reflector for automobile head lamps, comprising hyperbolic sections, one of said sections projecting a concentrated beam of high candle-power, two of said sections projecting bands of reduced illumination merging with the central beam and extending obliquely downward and outward, and two other of said sections projecting oblique bands of greater area and less illumination superimposed upon the first mentioned oblique bands, substantially as set forth. 65

4. A reflector for automobile head lamps, comprising hyperbolic sections, two of said sections projecting superimposed concentrated beams of high candle-power, another two of said sections projecting oblique bands of reduced illumination, said bands merging with the central beam and extending downward and outward, and two further sections projecting oblique bands of greater area but less illumination superimposed upon the first mentioned bands, substantially as set forth. 75 80

This specification signed and witnessed this 31st day of January, 1922.

WILLIAM F. LITTLE.
